(57) **CLAIM**

The ornamental design for a combined pedestal base, support bracket, and height adjustment button for adjustable height table, as shown and described.

DESCRIPTION

FIG. 1 is a top perspective view of the combined pedestal base, support bracket, and height adjustment button for adjustable height table;

FIG. 2 is a bottom perspective view of the combined pedestal base, support bracket, and height adjustment button for adjustable height table;

FIG. 3 is a side elevation view of the combined pedestal base, support bracket, and height adjustment button for adjustable height table;

FIG. 4 is an end elevation view of the combined pedestal base, support bracket, and height adjustment button for adjustable height table; and,

FIG. 5 is a bottom plan view of the combined pedestal base, support bracket, and height adjustment button for adjustable height table.

The broken lines shown in the figures are included for the purpose of illustrating the environment and form no part of the claimed design.

1 Claim, 5 Drawing Sheets
